UNITED STATES PATENT OFFICE

JOHN FOX, OF REGINA, SASKATCHEWAN, CANADA

GAS GENERATOR

Application filed August 29, 1927. Serial No. 216,241.

One of the principal objects of my invention is to provide a gas generator particularly devised for generating a gas for treating seed grain to kill parasitic spores lodged thereon, in a simple, inexpensive and efficient manner. Altho this is the specific use for which it has been devised it is equally efficient as a producer of fumigating and other similar gases.

10 Further specific objects are to provide simple and efficient means for admitting the materials to be gasified, producing gasification, removal and delivery of such gases and for assembly and separation of the parts for 15 storage, cleaning and inspection.

Such details are hereinafter described with reference to the accompanying drawings, in which:—

Fig. 1 is a vertical section thru such generator, and an elevation of the gas distributing apparatus; and

Fig. 2 is a fragmentary section thru the latter.

My improved gas grain generator a is divided into two chambers the upper one a' constituting a gas generator chamber and the lower one a^2 a heating chamber. Such chambers are separated by an imperforate, transverse, horizontal partition b , preferably formed with a depressed flat portion b' and upwardly arranged peripheral portions thus making such partition resemble somewhat a pie plate having a down turned rim portion, which is fastened to the walls of the generator by rivets b^2 or otherwise.

The gas generator chamber a' is substantially imperforate except for an aperture at the top over which the fitting c is mounted and connected into such aperture by a threaded nipple d . Secured about such aperture and fixed within such gas making chamber a' is a lock nut e' adapted to engage such nipple d and a similar nut e , freely rotatable, but threaded upon such nipple, is arranged 45 upon the exterior thereof.

In vertical alinement with such fitting c , is a filling aperture, capped by a plug f . Extending laterally from such fitting c is a perforate distributing pipe h and a pressure fitting i . Such gas distributing pipe h is

closed at its end by a cap h' and the perforations h^2 permit the gas to escape therefrom.

Such distributing pipe, when such gas generator is used for treating grain, is extended into a body of such grain approximately at 55 the bottom of such body and the germicidal gas generated is permitted to filter across such body to effect a lethal influence upon such parasitic germs.

The pressure fitting i carries a standard 60 tire valve j so as to permit a tire pump to be used for producing pressure in such distributing pipe and such gas generating chamber a' when it is desired to expel the gas from such chamber.

In the heating chamber a^2 a container g is centrally arranged below the partition b , such container being adapted to receive a supply of liquid fuel to be used as the heating agent. Such container is carried by a transverse bar l releasably engaging a bead n extending about the generator wall, as shown in Fig. 1.

Slightly below the flat portion b' of such partition b are a series of spaced air vents n extending thru the wall of such generator and above such air vents and about the upwardly extended portion of the partition b is formed a closed pocket adapted to trap the products of combustion and the heated air, thus to retain them to aid in the efficient heat 80 transfer, in gasification.

I claim:

In a device of the character described, a gas generator divided into stacked chambers, one constituting a gasifying chamber and the other a heating chamber, gas distributing devices leading out of such gasifying chamber and comprising a central member carrying laterally extending arms, one of such arms being a tubular member of substantial length provided with a plurality of small orifices, another a valved pressure connection extending in alinement with such first mentioned arm for producing flow of gas thru the latter, other arms in alinement with each other and arranged normal to such first mentioned pair of arms, and one extending into such gasifying chamber, the other carrying a removable capping element.

JOHN FOX.
